DESIGN FOR A CIRCULATING HEATER

Lafayette H. Caldwell, Lookout Mountain, Tenn.

Application March 1, 1945, Serial No. 118,196

Term of patent 7 years

(Cl. D81—19)

To all whom it may concern:

Be it known that I, Lafayette H. Caldwell, a citizen of the United States, residing at 523 Fleetwood Drive, Lookout Mountain, Chattanooga, county of Hamilton, and State of Tennessee, have invented a new, original, and ornamental Design for a Circulating Heater, of which the following is a specification, reference being had to the accompanying drawings, forming part thereof.

Figure 1 is a front elevational view of a circulating heater showing my new design.

Figure 2 is a side elevational view of same.

Figure 3 is a top plan view thereof.

I claim:

The ornamental design for a circulating heater, as shown.

LAFAYETTE H. CALDWELL.
